DESIGN.

M. TURNER.

LADY'S COSTUME.

No. 15,505.

Patented Oct. 28, 1884

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,505, dated October 28, 1884.

Application filed August 7, 1884. Term of patent 3½ years.

To all whom it may concern:

Be it known that I, MARY TURNER, of the city, county, and State of New York, have invented and produced a new and original Design for a Pattern of a Lady's Costume, (numbered 9,358;) and I do hereby declare that the engraved prints accompanying this specification convey to any one accustomed to using paper patterns a clear understanding of how a garment made up by the pattern will appear.

The design shows a round walking-skirt and an overdress. The skirt exhibits a deep plain front panel falling to the bottom of the skirt and outlining-points at the lower edge, front draperies that display draping plaits in their back edges, flare widely in deep points at the bottom, and appear to lap quite broadly at their front edges at the top. The overdress exhibits closely-fitted basque-fronts that shape

a point at each side of the closing and a curve over the hips, a deep closely-fitted basque-back, upon which appears to be draped a deep full back drapery that displays draping plaits in its center at the top, and also lower down at the center and in the front edges, and a deep opening in the lower part of the center, a standing collar, and coat-sleeves showing their wrists having reversed cuffs flaring at their back edges.

What I claim as my invention, and desire to secure by Letters Patent, is—

The design for a lady's costume, as shown in the engraved prints accompanying this specification.

MARY TURNER.
